UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

MULTIPLE-MAGAZINE TYPOGRAPHICAL COMPOSING-MACHINE.

1,222,120.

Specification of Letters Patent.

Patented Apr. 10, 1917.

Application filed December 5, 1916. Serial No. 135,252.

To all whom it may concern:

Be it known that I, CARL MUEHLEISEN, a citizen of the United States of America, residing at Chausseestrasse 23, Berlin, N. 4, in the Empire of Germany, have invented new and useful Improvements in Multiple-Magazine Typographical Composing-Machines, of which the following is a specification.

This invention relates to typographical 10 composing machines such as those known commercially under the trade mark "Linotype" and kindred machines, and particularly it relates to those machines which are provided with a column of superposed magazines 15 adjustable to bring any of the latter into operative or composing position, and in which the escapements are actuated by rods which, before and after the magazines are so adjusted, must be moved respectively out of 20 and into the path followed by the magazines or escapements during such adjustment.

It has heretofore been proposed to effect the raising and lowering, hereinafter termed "shifting", of the column of magazines by 25 means of crank-actuated screw gear the crank being rotated by hand and provided with special means whereby the escapement rods could be moved as aforesaid, before and after the shifting of the magazines.

30 In the just mentioned arrangement, as well as in all others previously suggested, the aforesaid movement of the escapement rods has involved a distinct action on the part of the operator, for example, axially moving 35 the crank shaft or operating a special lever, and the object of the present invention is to provide means of such construction that the said movement of the escapement rods and the shifting of the magazines are both effect- 40 ed by a single act on the part of the operator, which does not call for any attention being especially directed to either independently of the other.

The invention may be said to consist essen- 45 tially in the employment, for shifting the magazines, of a worm or screw the thread of which is so formed that, during the period at which the escapement rods are to be moved out of and into the aforesaid path, no motion will, by the rotation of such screw, be imparted to the magazines, and vice versa.

The invention will now be described by reference to the accompanying drawings in which:—

55 Figure 1 is a side elevation of a six-maga-

zine machine provided with the improved mechanism according to the present invention;

Fig. 2 is a sectional elevation of a part of the magazine-shifting gear; 60

Fig. 3 is a vertical section on or about the line 3—3 of Fig. 2, and

Fig. 4 is a view of the means for moving the escapement rods out of and into operative position. 65

In these drawings, *a* is the machine frame, *b* the magazines supported upon a common frame *c*, to which latter are secured toothed bars or racks *d* meshing with spur wheels *e*. The wheels *e* are fast upon shafts *f* which 70 are correspondingly rotated by worm gearing, for which purpose the said shafts have secured thereon disks *g* having studs or rollers *g*¹ angularly distributed thereon at uniform distances apart and with which 75 studs the worms *h* operatively engage. The two worms *h* are both secured upon the same shaft *i* upon which is also secured a cam *k* which serves for moving the escapement rods 80 *l* out of and into operative position, this cam 80 serving to rock an angle lever *m* about its pivot *m*¹. As shown in Fig. 4, the cam *k* is provided with a peripheral depression in which the lever *m* rests when the machine is 85 in operative position, *i. e.* when the escapement rods *l* are, as shown in Fig. 1, in position to engage the escapements of the respective magazine. 85

On the shaft *i* is secured a crank handle *n* by which it can be rotated, and when it is so 90 rotated, the angle lever *m* will first be moved and thereby withdraw the escapement rods *l* out of their operative position.

Each of the worms *h*, as illustrated in 95 Figs. 2 and 3, has a flat surface or portion *o* located in a plane perpendicular to the axis of the shaft *i*, so that when this shaft is rotated anti-clockwise or clockwise in order 100 respectively to lower or raise the magazines, the first part of such rotation will have no effect upon the column of magazines which, during that period, will remain stationary. Meanwhile, however, the angle lever *m* has completed its movement and the escapement rods *l* have been withdrawn as before 105 stated, and it is only when the flat surface *o* has passed beyond the respective stud *g*¹ that the actual shifting of the magazines 110 commences. Each rotation of the shaft *f* withdraws the escapement rods *l* as afore-

said, moves the column of magazines a distance equal to the thickness of a magazine plus the distance between any two adjacent magazines, and restores the escapement rods into their operative position.

Each of the disks g with its complement of studs g^1 is herein regarded as a worm-wheel and, for convenience, is referred to as such in the following claims.

10 Having described my invention, I declare that what I claim and desire to secure by Letters Patent is:—

15 1. In a multiple-magazine typographical composing machine, the combination with a column of magazines, and a worm-wheel in operative connection therewith to shift said column, of a worm coöperating with the worm-wheel, and a flat surface on said worm, with which the teeth or studs of the 20 worm-wheel engage at the commencement of the magazine-shifting operation, so that the worm can be partially rotated without shifting the magazines.

25 2. In a multiple-magazine typographical composing machine, the combination with a column of magazines, and a worm-wheel in operative connection therewith to shift said column, of a worm coöperating with the worm-wheel, a flat surface on said worm enabling the worm to be partially rotated without shifting the magazines, escapement rods adapted to actuate escapements on the 30 magazines and devices operating conjointly with the worm disengaging the escapement rods from and engaging them with the escapements during the periods at which the 35 worm rotates without shifting the magazines.

3. In a multiple-magazine typographical composing machine, the combination with a column of magazines, and a worm-wheel in operative connection therewith to shift said column, of a worm coöperating with the worm-wheel, a flat surface on said worm enabling the worm to be partially rotated without shifting the magazines, escapement rods adapted to actuate escapements on the magazines and a cam operatively fast to the worm operative to disengage the escapement rods from and engage them with the escapements during the periods at which the worm rotates without shifting the magazines.

4. In a multiple-magazine typographical composing machine, the combination with a column of superposed magazines, a magazine frame supporting said column, a toothed rack attached to said magazine frame, a spur wheel engaging the rack and a worm-wheel operatively fast to the spur wheel, of a worm coöperating with the worm-wheel, a flat surface on said worm enabling the worm to be partially rotated without shifting the magazines, escapement rods adapted to actuate escapements on the magazines and a cam operatively fast to the worm operative to disengage the escapement rods from and engage them with the escapements during the periods at which the worm rotates without shifting the magazines.

In witness whereof I have hereunto set my hand in the presence of two witnesses.

CARL MUEHLEISEN.
